LEONHARD RODENHAUSEN, OF PHILADELPHIA, PENNSYLVANIA.

Letters Patent No. 67,805, dated August 13, 1867.

IMPROVEMENT IN STREET-SPRINKLING CARTS.

The Schedule referred to in these Letters Patent and making part of the same.

TO ALL WHOM IT MAY CONCERN:

Be it known that I, LEONHARD RODENHAUSEN, of the city and county of Philadelphia, and State of Pennsylvania, have invented a new and useful Improvement in Sprinkling-Apparatus; and I do hereby declare the following to be a full, clear, and exact description of the nature thereof sufficient to enable others skilled in the art to which it appertains to fully understand and use the same, reference being had to the accompanying drawings, making part of this specification, in which—

Figure 1 is a side view of the device illustrating my invention.

Figure 2 is a rear view of the same.

Figure 3 is a plan or top view thereof.

Figure 4 is a longitudinal vertical section of the same in line $x\ x$, fig. 3.

Figure 5 is a top view of the strainer.

Figure $5\frac{1}{2}$ is a longitudinal vertical section in line $y\ y$, fig. 5.

Figure 6 is a front view of the valve.

Figure 7 is a transverse vertical section thereof in line $z\ z$, fig. 6.

Figure 8 is a longitudinal vertical section in line $z'\ z'$, fig. 6.

Similar letters of reference indicate corresponding parts in the several figures.

This invention consists in applying a valve to the spreader or sprinkler, whereby the water can instantly be shut off therefrom when desired. It also consists in applying a strainer to the cart or induction tube, so that sticks and dirt cannot enter the cart, and thus clog or choke the spreader or sprinkler; the parts being simple in construction, and arranged so as to be easily operated, as will be hereinafter more fully described.

In the drawings, A represents the body of a cart, closed on all sides, and mounted on ordinary running-gear B, and provided with a seat, a , and step, b . The bottom or lower side b' of the cart is inclined towards its rear, whereby the cart can be properly drained of any water which might remain on the bottom, and thus prevent premature rotting of the wood. C is the induction pipe, arranged on the upper side or top of the cart, at the lower termination of which is attached or suspended a strainer, D, consisting of a box, having a sieve or netting applied thereto. Any matter, whether dirt, sticks, or the like, which may flow with the water into the cart, will be intercepted by the strainer, and be prevented from entering into the cart. Otherwise the spreader or sprinkler would be clogged or filled, so that the water cannot flow freely out of the spreader. This has been a serious objection to sprinkling-devices hitherto, a cleansing of the spreader being necessary every day while in use.

The body of the cart is closed, as will be readily seen, and all splashing of the water is obviated. In ordinary sprinkling-carts the means of introducing water are by doors or gates on the top of the cart. These doors are opened, and one end of the hose hangs in the cart. When the cart is full, the doors are closed, and the great body of water, while the cart is in motion, will naturally cause great agitation and splashing against the doors. Although these require means of fastening, the rough usage will soon cause them to break and wear out, and the water will have exit, and splash the driver and passers-by. The construction of my cart will remedy this evil, as well as present an attractive appearance. I have introduced them into use, and have had great demand for them as advertising mediums.

The induction-pipe C obviates the necessity of doors or gates. I design to connect a hose thereto, and carry the same in a grating or receptacle, E, at the rear of the cart. The hose can remain on the plug, if desired, and applied and screwed to the pipe C as ordinary. This, however, is not so good as carrying the hose with the cart, for in case of fire the hose must be detached from the plug, which will occupy some time. The grating or open support for the hose will admit of draining the hose, so that the same will be capable of drying while being carried with the cart. On the forward end of the body, above the step b , is pivoted a foot-lever, c , to which is pivoted an angular lever, d , whose bearing is on the upper side of the body A. e is a lever pivoted at the rear end of lever d , to the bottom of which is secured a sliding-valve, F, of ordinary construction. From the lower side of the body A projects, downwardly and outwardly, the eduction tube G, which is connected at right angles to the spreader and sprinkler H. Suitable brace-rods f extend from the body A, are connected to

the spreader or sprinkler, and form means of retaining and supporting the spreader. At the point where the tube G connects the spreader H, I place the valve F.

It will be seen that just at the point where the water enters the spreader I apply my valve, the advantage of which is as follows: Pedestrians have found serious annoyance in the sloppy and wet crossings caused by the spilling or splashing of water from the carts. The driver often neglects to shut off the same in proper time, and, should he be prompt, there is plenty of water in the spreader or sprinkler to wet the crossing nevertheless. Valves in sprinkling-carts are always placed inside of the water-receiver or body, and the above annoyances are the result of such arrangement. These my improvements are intended to obviate.

The eduction pipe may be curved or perfectly cylindrical, and the construction of the sprinkler likewise. A portion or all of the eduction pipe may be made of flexible material, but if otherwise, will assist in supporting the sprinkler.

The operation is as follows: The valve F is closed, and a hose attached to the induction pipe C, and connected to a plug or other suitable supply. When the water is turned on, and fills the body A, it will overflow through a small orifice or opening in the body, and then the water will be turned off. When the driver wishes to water the street, he raises the valve, by means of the levers c d e, and the water will fill the spreader and flow out through the perforations in the same. Should he desire to shut off the water in passing over a crossing, or over the same road or street a second time, or in turning a corner, or for any reason whatever, he closes the valve, and the supply of water to the spreader ceases at once. All dirt or matter which would clog the spreader will be collected in the strainer D before the water enters the body of the cart, and can be removed at suitable times. When the device is no longer needed, the valve is opened, and all water in the body will pass out. The inclined bottom b' will assist in this purpose, and afford no place for lodgment or collection of water. Air will readily pass in and out of the induction and eduction tubes, and the inside of the body will have ample means for drying.

My improvements are simple in construction, but exceedingly useful and practical. The means for operating the valves can be varied, although I prefer to use such as are shown. They are concealed by side and back pieces extending upwards from the body A, and the space enclosed therein forms a place for the driver's coat, and whip, and lunch, as well as for storing feed for the animals and buckets for their drink, besides giving the driver a comfortable seat, and one where he is not liable to be thrown off by the jarring or shaking of the cart, consequent to the agitation of the water.

Having thus described my invention, what I claim as new, and desire to secure by Letters Patent, is—

1. A sprinkling-cart, constructed with the following characteristics, viz: A closed body, A; an inclined bottom, b; the hose-rack E, and strainer D, arranged and operating substantially as described.

2. I claim, in combination with the body A, the valve F, placed at the junction of the eduction pipe and sprinkler, substantially as specified.

To the above I have signed my name this 6th day of May, 1867

L. RODENHAUSEN.
